BRINE TANK ELEVATOR

Tamis C. Schenk, Richmond Hill, N. Y., assignor,
by mesne assignments, to Fruit Products Cor-
poration, New York, N. Y., a corporation of
New York

Application April 5, 1950, Serial No. 154,115

8 Claims. (Cl. 134—134)

1

As conducive to an understanding of the invention, it is to be noted that in the manufacture of stick-held confections, the sticks on which the confections are to be formed are retained in a conventional stick holder which is then placed in a mold filled with a suitable mix to form the confection. The filled mold and stick holder which form a relatively heavy unit, in the order of approximately 35 lbs., are lowered into a brine tank and advanced therethrough in order that the mix may solidify.

Where such procedure requires an attendant manually to lift up the relatively heavy units and then lower the same into the brine tank, he can only function at a relatively slow speed with resultant low output and as, during the course of a day, many hundreds of units must be deposited in the tank, the resultant relatively great physical strain may cause severe injury to the attendant.

In addition to such physical strain and low output, the attendant is likely to tilt the unit while lowering the latter into the tank which may cause the mix in the mold to spill therefrom with resultant variations in the shape and size of the confection formed, or spread over the top of such mold with the result that a layer of frozen mix would join the upper ends of the stick-held confections. This would add to the cost of the finished product in that the additional step of manually breaking such layer would be required in order that the individual confections could be removed.

It is accordingly among the objects of the invention to provide an elevator that may readily be installed in a conventional brine tank with but slight, relatively simple modifications in the construction thereof, which elevator has but few, inexpensive, sturdy parts that are not likely to become out of order and which will gradually lower the filled mold and stick holder unit into the brine tank without any exertion on the part of the attendant or without any likelihood of tilting of such mold during such lowering operation.

Another object of the invention is to provide an elevator of the above type which may coact with the pusher bar of the conventional brine tank to lower a mold and stick holder unit into the brine tank in timed relationship with the advance of the units previously lowered into such tank and without likelihood of the last lowered unit interfering with the units previously lowered into such tank.

A further object of the invention is the provision of a mold elevator for conventional brine

2

tanks, which is actuated by a reciprocating pusher bar, whereby the molds will first be lowered in a horizontal plane to substantially in alignment with the submerged trackways, and then the pusher bar passes over the elevator to engage the molds positioned thereon and push them off said elevator onto their respective trackways.

Another object of the invention is to provide a simple and effective means for lowering a plurality of molds into a circulating brine of a conventional brine tank in alignment with a plurality of submerged trackways, remove the molds from said lowering means onto said trackways, and then return said lowering means to its normal mold receiving position above said brine adjacent the receiving end of said tank.

According to the invention the elevator is incorporated into a conventional brine tank of the type having pairs of tracks extending longitudinally thereof to guide rows of mold and stick holder units along the length of the tank so that the mix in the molds may be frozen, the brine tank having means to engage the rearmost unit in such row intermittently to advance the units through the tank. The elevator, one of which is associated with each of such pair of tracks, desirably includes a tray which is mounted, preferably by a parallel motion linkage, on the floor

of the tank in horizontal position and capable of reciprocable movement with respect to such floor both in a forward downwardly direction and in a rearward upwardly direction. Thus when a unit is placed on the tray when the latter is in its upper rearmost position, the unit may simultaneously be lowered and advanced in horizontal position onto such pair of tracks. The elevator is operatively connected to the pusher bar of the brine tank, which bar extends transversely across such tank and is reciprocable in the same direction as is the tray. The connection between the elevator and pusher bar is so arranged that when the latter is in its rearmost position preparatory to advancing the units in the tank, the tray portion of the elevator will be in its uppermost position and as the pusher bar is advanced to its forwardmost position, the tray will be lowered until the unit thereon lies on the associated pair of tracks in such brine tank, continued forward movement of the pusher bar causing the latter to engage the rear wall of the mold portion of the unit to advance the latter off the tray forwardly along such pair of tracks. At this time the pusher bar will be moved in a rearward direction and in such rearward motion thereof

40

45

50

55

will lift the tray to its uppermost position ready to receive another unit. The next forward movement of the pusher bar will cause the latter to again lower the tray and deposit the unit thereon, immediately to the rear of the unit previously placed on such pair of tracks. Continued forward motion of the pusher bar will move the unit last deposited forward on the pair of tracks and cause such unit to advance the unit immediately preceding the same.

In the accompanying drawings in which is shown one or more of various possible embodiments of the several features of the invention,

Fig. 1 is a fragmentary perspective view of a brine tank having an elevator installed therein and in uppermost position,

Fig. 2 is a fragmentary end view of the tank taken along line 2—2 of Fig. 1,

Fig. 3 is a longitudinal sectional view taken along line 3—3 of Fig. 2,

Fig. 4 is a view similar to Fig. 3 showing the elevator in lowered position,

Fig. 5 is a fragmentary perspective view of the elevator shown in Fig. 1, showing in greater detail the mechanism for operating the reciprocating pusher bar, and

Fig. 6 is a cross-sectional view taken substantially along the line 6—6 of Fig. 5, showing details of the drive for the operating mechanism.

Referring now to the drawings, the brine tank 11 which is conventional in construction, has a floor or base 12 beneath which the freezing coils 13 are positioned. Extending longitudinally of the brine tank 11 on the floor 12 thereof are a plurality of pairs of tracks 14 and 15, which are 30 desirably angle irons, as shown, each of said pairs of tracks serving to guide a row of units, each including a mold 16 with a stick holder (not shown) therein through the brine tank.

Means are desirably provided intermittently to advance the units along the tracks 14 and 15 through said brine tank. To this end, a pusher bar 17 is desirably provided, extending transversely across the tank 11 at the input end thereof of parallel to the floor 12.

The pusher bar 17 is so mounted that it may be reciprocated at right angles to its length in said tank, a distance greater than the length of each of the units. Although any suitable means may be used to mount the pusher bar 17, in the embodiment herein shown, each end 18 of the bar is affixed as by welding to the end of the vertical leg 19 of a substantially L-shaped bracket 21, the horizontal leg 22 of which is desirably affixed to a block 23 riding in a channel 24 mounted on the side walls 25 of the tank near the input end thereof.

According to the invention, means are provided automatically to lower a unit onto each of the pairs of tracks 14 and 15, in timed relation with the advance of the transverse pusher bar 17 in the tank. To this end an elevator is associated with each of said pairs of tracks, which elevator as shown in Fig. 1, desirably comprises a tray 28 having a substantially rectangular, preferably perforated floor 29, of width desirably slightly less than the distance between the spaced angle irons 14, 15 forming each of the pairs of tracks, and of length desirably but slightly greater than the length of a conventional mold 16. The tray 28 has an upstanding wall 31 along each of the longitudinal edges thereof, said walls having outwardly extending flanges 32 at the upper edges thereof desirably formed integral therewith.

In order to mount the tray 28 in the brine tank 11 so that it may be longitudinally aligned with the pair of tracks 14 and 15, a plurality of linkage arms 33 of substantially identical length are provided, desirably positioned in pairs on each side of the tracks 14 and 15. The lower ends of each of said linkage arms are pivotally mounted, preferably by means of horizontal pins 35 through hubs 36 respectively, the latter being desirably formed integral with each of the ends of a strip 37 affixed as by bolts 38 to the floor 12 of the brine tank and positioned adjacent to and extending longitudinally of the outer face 39 of each of the pairs of angle irons which form the tracks 14 and 15.

The upper ends of each pair of the levers are pivotally mounted with respect to the tray 28, preferably by means of horizontal pins 42 through hubs 43 respectively, the latter being desirably formed integral with each end of a strip 44 positioned beneath each of the outwardly extending flanges 32 and clamped to such flanges by means of bolts 46, which extend through such strip 44 and through a strengthening strip 47 positioned on the upper surface of each of said flanges.

As the distance between the hubs 43 at the upper ends of the linkage arms 33 is equal to the distance between the hubs 36 at the lower ends of the arms and as the length of the arms are also equal, it is apparent that a parallel motion may be imparted to the tray 28 through the linkage thus described arms.

In order to actuate such parallel motion linkage, a stop 48 in the form of an arm having an oblique upwardly extending portion 49 is affixed as by welding near the lower ends of the rearmost arms 33 of the elevator. The stop 48 is so positioned that, as shown in Figs. 1 and 3, when the pusher bar 17 is in its rearmost retracted position, it will engage the oblique portion 49 of the stop 48 with the levers 33 inclined forwardly with respect to floor 12. Thus, the weight of the tray will retain the oblique portion 49 of the stop 48 against the pusher bar 17 and hence retain the tray 28 in its uppermost position, and when the pusher bar 17 is advanced and moves away from the oblique portion 49 of the stop 48, the tray 28 will be both advanced and lowered to its lowermost position as shown in Fig. 4, and the upper end 50 of the oblique portion 49 will lie in the path of the return movement of the pusher bar 17 so that it may be engaged thereby.

In the operation of the installation, when the pusher bar 17 is in its rearmost position engaging the oblique portion 49 of the stop 48, as shown in Fig. 3, the tray 28 will be in its uppermost position with its floor 29 substantially horizontally aligned with the upper surface 11' of the front end of the brine tank. It is therefore a relatively simple matter for the attendant to slide a mold and stick holder unit onto the tray without need for him to bend or stoop. The pusher bar drive mechanism may thereupon be actuated to advance the pusher bar 17 along channels 24 which will move the pusher bar 17 away from the obliquely extending portion 49 of the stop 48. As a result of the forward movement of the pusher bar, the weight of the unit on the rack will cause the linkage arms 33, which are in forwardly inclined position, to pivot forward at their lower ends in the associated hubs 36. By reason of the pivotal connection of the upper ends of the arms to the side walls 31 of the tray, a parallel motion will thereupon be im-

parted to such tray gently to lower and to move the unit thereon forwardly with such tray until the floor of the latter is positioned between the angle irons forming a pair of tracks as shown in Fig. 4, the perforated floor of such tray permitting passage of liquid therethrough to facilitate its movement through the liquid in the brine tank.

In order to prevent closure of the perforations in the floor by the bottom of the unit when it is placed on the tray, the mold 16 is spaced from such floor 29 by longitudinal spacer plates 60 affixed to the edges of the floor of the tray and extending longitudinally thereof, said spacer plates carrying the unit thereon.

During the course of the forward movement of the tray, as shown in Fig. 4, when such tray is on the floor 12 of the brine tank, the pusher bar 17 will have moved away from the oblique portion 49 of the stop 48 and will thereupon abut against the rear wall 26 of the unit. Continued advance of the pusher bar 17 will thereupon slide the unit off the tray between the associated pair of tracks 14 and 15 to the position shown in Fig. 4. At this time the movement of the pusher bar 17 will be reversed, whereby it is reciprocated and move back to its original position. As the upper end 50 of the oblique portion 49 of the stop 48 is in the path of movement of the pusher bar 17, when the latter engages such stop 48, it will pivot the linkage arms 33 and the resultant parallel motion imparted to the tray will cause the latter to be simultaneously moved rearwardly and lifted to its original position ready to receive another unit.

As successive units are placed on the tray and lowered into the brine tank and advanced off the tray 28 in the manner thus described, the front end of such units will be moved against the units previously lowered into the tank and the pusher bar will thereupon advance said units along the track. This procedure will be repeated as successive units are placed on the tray with the result that the plurality of units on each of the pairs of tracks will be intermittently advanced along through the brine tank.

Referring now to Figs. 5 and 6, there is shown suitable driving or operating mechanism for reciprocating the pusher bar 17 longitudinally of the brine tank 11, whereby the molds 16 are pushed off the elevator trays 28 onto the tracks 14 and 15 extending longitudinally thereof.

As best shown in Fig. 6, there is mounted fixedly on the tops of each of the elongated blocks 23, which are slideable in the channel guides 24 extending along each side 25 of the brine tank 11, suitable gear racks 66 and 67, which extend inwardly from the input end of the tank 11 a distance slightly longer than the length of one mold 16. The gear rack 66 meshes with a spur gear 69, and the gear rack 67 meshes with a second and similar spur gear 71 (see Fig. 6). The spur gears 69 and 71 are keyed to a transversely extending drive-shaft 72 journaled in suitable spaced bearing supports 73 and 74. The drive-shaft 72 is enclosed in a tubular housing 75. The drive-shaft 72 has a worm wheel 77 secured fixedly, as indicated at 78, to the end thereof extending beyond the spur gear 71. The worm wheel 77 meshes with a worm 79 keyed to a drive shaft 80 of a conventional gear reduction box 81; which, in turn, is connected directly with a drive shaft 82 of a conventional reversible electric motor 83, which is energized and controlled through a conventional starter box 84, having a series of con-

trol buttons 86, 87 and 88 for manually starting, stopping and reversing the motor 83, respectively.

The normal position of the elevating apparatus is its loading position, which is best shown in Figs. 1 and 5 of the drawings, wherein the trays 28 are in an elevated position to receive filled molds 16. Assuming the apparatus is in such a normal position with its trays 28 loaded with molds 16, the electric motor 83 may be energized by manually pushing the starter button 86 of the control box 84. The motor 83 operating normally through the gear reduction box 81 drives the drive shaft 72 and its fixed spur gears 69 and 71 in a counterclockwise direction. Operating in this manner, the spur gears 69 and 71 will draw their respective gear racks 66 and 67 inwardly of the tank 11, pulling their fixed blocks 23 inwardly of the channel guides 24, which, in turn, through the connecting brackets 21 draw the pusher bar 17 longitudinally inwardly or forwardly of the tank 11, thereby forcing the elevator trays 28 downwardly and eventually pushing the molds 16 therefrom onto the submerged tracks 14 and 15 extending longitudinally through the brine tank.

When the gear rack 67 moves inwardly or forwardly the desired distance, it strikes a finger 91 operating a conventional electric reversing switch 92 (shown diagrammatically in Figure 1), which automatically causes the motor 81 to stop and then start up in a reverse direction. With the motor 81 now operating in a reverse or in a clockwise direction, the drive shaft 72 will also be rotated in a clockwise direction, causing its fixed spur gears 69 and 71 to turn in the same direction, which will draw the gear racks 66 and 67 rearwardly or toward the input end of the brine tank, thereby causing the pusher bar 17 to be moved rearwardly in the same direction, which, in turn, will engage the cam arms 49 projecting rearwardly and upwardly from the rear pivotal arms 33 for supporting the trays 28 and carry them rearwardly also. It will thus be appreciated that in this manner the elevator mechanism is always returned to its normal mold receiving position.

As the gear rack 67 is moved rearwardly into its normal mold receiving position, as best shown in Figure 5, its forward end will engage a finger 95 operating a conventional limit switch 97, which turns off the electric current to the motor 81, thereby bringing the operating mechanism to a stop in its normal raised position. The motor 81 may again be energized by manually pushing the starter button 86 for repeating the operating cycle. The control button 87 is a manual emergency control for stopping the motor 81 at any time during its cycle. The control button 88 is a manual starting button for causing the motor 81 to be started in its reversing direction in the event the operating mechanism had to be stopped by the control button 87 during the reversing portion of its cycle.

With the construction thus described, a relatively simple structure is provided which may readily be incorporated with low cost and with but few changes in a conventional brine tank and will enable relatively heavy molds and stick holder units to be deposited in such brine tank with but little effort and strain on the part of the attendant and, consequently, he may function at a much greater rate of speed with resultant enhanced output and also as he does not have to bend to deposit the mold into the tank, there is

little likelihood of tilting of such mold with resultant spilling of the contents thereof which would cause the confections not to be uniform with the result that some of them might be unsaleable.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. In combination with a brine tank having a submerged mold receiving trackway extending horizontally thereof and a reciprocating pusher bar mounted transversely of the trackway adjacent the receiving end of said brine tank above the level of the brine thereof, a mold elevator including a horizontal tray mounted pivotally longitudinally above said trackway and forwardly of said pusher bar, said tray in its normal mold receiving position extending above said brine and adjacent the receiving end of said tank, means for reciprocating said pusher bar whereby said tray is moved forwardly and downwardly in a horizontal position until it is in substantial alignment with said trackway and below the plane of travel of said pusher bar whereby the latter engages the rear end of said mold and pushes it off said tray onto said trackway.

2. In combination with a brine tank having a spaced submerged mold receiving trackway extending horizontally and longitudinally thereof, and a reciprocating pusher bar mounted transversely adjacent the receiving end of said trackway above the level of the brine in said tank, a mold elevator including a horizontal tray mounted pivotally on said trackway and movable longitudinally thereof, said tray in its normal mold receiving position extending above said brine and adjacent the receiving end of said tank, means for reciprocating said pusher bar whereby said tray is moved forwardly and downwardly onto said trackway and below the plane of travel of said pusher bar so that the latter may engage the rear end of said mold and push it off said tray onto said trackway.

3. In combination with a brine tank having a spaced submerged mold receiving trackway extending horizontally and longitudinally thereof and a reciprocating pusher bar mounted transversely adjacent the receiving end of said trackway above the level of the brine in said tank, a mold elevator including a horizontal tray mounted pivotally on forwardly inclined arms above said trackway and movable longitudinally thereof, said tray in its normal mold receiving position extending above said brine and adjacent the receiving end of said tank, means for reciprocating said pusher bar whereby it engages the arms of said tray and moves them forwardly and downwardly onto said trackway and below the plane of travel of said pusher bar which continues to move forwardly engaging the end of said mold and pushing it off said tray onto said trackway, said inclined arms adjacent said pusher bar having means engageable by said pusher bar on its return movement to raise said tray to mold receiving position in said brine tank.

4. In combination with a brine tank having a submerged mold receiving trackway and a re-

ciprocating pusher bar mounted transversely thereof adjacent the receiving end of said trackway above the level of the brine in said tank, a mold elevator including a horizontal tray mounted pivotally adjacent opposite ends and movable longitudinally above said trackway, said tray having its normal mold receiving position extending above said brine and adjacent the receiving end of said tank, and means for reciprocating said pusher bar on a horizontal plane longitudinally of said trackway above the brine level in said tank whereby said tray is moved forwardly and downwardly by said pusher bar until it is in substantial alignment with said trackway so that said pusher bar may engage the end of the mold on said tray and push it off onto said trackway.

5. In combination with a brine tank having a plurality of spaced submerged trackways extending longitudinally thereof and a reciprocating pusher bar extending transversely of said trackways adapted to be moved horizontally thereover above the brine level thereof, a mold elevator including a plurality of horizontally mounted trays having pivotally mounted upstanding arms extending above said pusher bar, said trays in their normal receiving position extending above the brine level of said tank, means for reciprocating said pusher bar above the liquid level of said brine whereby said pusher bar engages the upstanding arms of said trays and pushes them forwardly and downwardly until said trays are in substantial horizontal alignment with said trackways and below the plane of said pusher bar whereby the latter may pass over said trays and engage the molds position thereon to push them forwardly off of said trays onto said trackways, and means carried by an upstanding arm of said trays for engaging the pusher bar on its return movement to raise said trays back to their normal mold receiving position.

6. In combination with a brine tank having a series of spaced submerged mold receiving trackways extending longitudinally thereof and a reciprocating pusher bar extending transversely thereof above the level of the brine in said tank, a mold elevator including a plurality of horizontal trays mounted pivotally on said trackways with one tray to each trackway, said pusher bar when in its normal position being between said trays and the receiving ends of said trackways, means for reciprocating said pusher bar whereby it engages the uprights for said trays when moving forwardly to force the same below the level of said brine and below its own horizontal plane of movement until said pusher bar engages the molds positioned on said trays and forces them onto their respective trackways, means including a limit switch and reversible motor for reversing the movement of said pusher bar when said mold is moved off said tray, means carried by the rearwardly arms of said tray for engaging said pusher bar on its return movement to cause said trays to be carried upwardly therewith to their normal mold receiving position, and means including a limit switch operated by said pusher bar mechanism for stopping said motor when the same has returned to its normal mold receiving position.

7. In combination with a brine tank having a series of spaced mold receiving trackways and a reciprocating pusher bar adapted to operate longitudinally of said trackways above the level of the brine in said tank, a mold elevator comprising a plurality of spaced rectangular horizontal

trays, each tray being mounted pivotally on four forwardly inclined spaced arms secured pivotally to its respective trackway, means for moving said pusher bar forwardly whereby it engages the rearwardly pair of upstanding arms of each tray forcing them forwardly and downwardly until said trays are aligned horizontally with their respective trackways whereby said pusher arm may pass over said trays to engage the molds positioned thereon and move them onto their respective trackways, means for stopping the forward movement of said pusher bar and causing it to return to its normal position, means adapted to be engaged by said pusher bar on its return movement for raising said trays to their normal receiving position, and means for stopping the movement of said pusher bar when said trays have been raised to their normal mold receiving position.

8. In combination with a brine tank having a series of spaced mold receiving trackways and a reciprocating pusher bar adapted to operate longitudinally of said trackways above the level of the brine in said tank, a mold elevator comprising a plurality of spaced rectangular horizontal trays, each tray being mounted pivotally on forwardly inclined upstanding spaced arms, the arms of each tray being also mounted pivotally to its respective trackway, means for moving said pusher bar forwardly of said trackways 20

5
10
15

whereby it engages the rearwardly inclined arms of each of said trays forcing them forwardly and downwardly until said trays are aligned horizontally with their respective trackways whereby said pusher arm may pass over said trays to engage the molds positioned thereon and move them onto their respective trackways, means for stopping the forward movement of said pusher bar and causing it to return to its normal position, means carried by a rearwardly upstanding arm for engaging said pusher bar on its return movement for raising said trays to their normal receiving position, and means for stopping the movement of said pusher bar when said trays have been raised to their normal mold receiving position.
